UNITED STATES PATENT OFFICE.

HIRAM B. MEARS, OF DUBUQUE, IOWA, ASSIGNOR OF ONE-HALF TO ASA HORR, OF SAME PLACE.

WATCH-MOVEMENT.

SPECIFICATION forming part of Letters Patent No. 296,204, dated April 1, 1884.

Application filed November 15, 1883. (No model.)

To all whom it may concern:

Be it known that I, HIRAM B. MEARS, of Dubuque, in the county of Dubuque and State of Iowa, have invented a new and useful Improvement in Watches; and I do hereby declare that the following is a full, clear, and exact description of the same.

My invention relates to improvements in watches; and the invention consists in various details of construction by which the mechanism of the watch-movement is simplified.

My invention relates to watches of that class in which the barrel is stationary, except when winding; and it consists of details of construction all as hereinafter fully set forth, and particularly claimed.

The invention is illustrated in the accompanying drawings, in which Figure 1 is a perspective of the main bridge and winding-arbor, showing the edge of the driving-wheel and ratchet. Fig. 2 shows opposite sides of the winding-arbor. Fig. 3 shows opposite views of the mainspring-barrel. Fig. 4 shows the driving-wheel. Fig. 5 shows the dial-plate. Fig. 6 is an elevation of part of the gearing, showing the manner of driving the hour-wheel.

A represents the winding-post, B the barrel, C the bridge, D the driving-wheel, F the ratchet, M the face-plate, and X the edge of the dial-plate, all shown in Fig. 1.

Secured to the winding-arbor A is a flat disk or plate, A', which turns with the arbor or post A in a sink or recess in the face of the bridge C. This plate is secured by screws or pins to the central part of the mainspring barrel, Fig. 3, so that the said barrel revolves with the post as the latter is turned. By this construction I am enabled to jewel the upper pivot of the driving-wheel, since the pressure in winding is all taken by the plate A', and there is no danger of breaking the jewel.

The barrel B is provided with a head, G, the edge of which is beveled and fitted to an annular groove in the inner surface of the barrel and at the end thereof, so that the head comes flush with the edge of the barrel.

The driving-wheel D has at one side a hub or arbor, E, Fig. 4, and upon the other a pinion, H. The arbor E revolves within a hole in the head G of the barrel in such a

manner that it has free revolution independently of the barrel and its head. The driving-wheel is fixed on the arbor and revolves with it independently of the barrel, which is stationary, except while winding. The main-spring is so connected to the barrel by its outer end that it is wound up from the outside by turning the barrel in the manner before described. The driving-wheel D turns in a sink in the plate M, which is deepened at the center to receive the pinion H on such driving-wheel. The pinion H gears directly into the hour-wheel J, Fig. 6, the pivot of which runs in a bearing in a bridge, P, and holds the hour-hand.

In Fig. 5 is shown the hour-dial divided into twenty-four spaces, around which the hand moves once in twenty-four hours. The minute-hand is driven from a central pinion, o, which meshes directly with the main drive-wheel D. This hand moves around the ordinary dial. On the shaft of the minute-hand is fixed a gear, W, which, through lantern-wheel and pinion Y Y', drives the second-hand, as shown in Fig. 5. The pivots of the three hands are thus placed on a line.

By the construction shown I am enabled to jewel every pivot of the watch, increasing its ease of movement and rendering it more durable.

Having thus described my invention, I claim—

1. In combination, the winding-post, disk A' in a sink or recess in the face of the bridge and attached to the stationary barrel, said barrel being provided with ratchet F beneath the bridge, the driving-wheel D, having an arbor, E, with bearing in the barrel, the spring, and the lower bearing for the wheel D, all these parts being arranged in a watch substantially as described.

2. In combination, the winding-post, disk A' in a sink or recess in the face of the bridge and attached to the stationary barrel, said barrel being provided with ratchet F beneath the bridge, and with a head, G, the driving-wheel D, having an arbor, E, with bearing in the barrel, the spring, and the lower bearing for the wheel D, all these parts being arranged in a watch substantially as described.

3. In combination, the stationary barrel

and ratchet F and winding-arbor, the spring, the wheel D, having its upper bearing in the barrel, the pinion H, and the hour-wheel J, with its bearing in bridge P, its hour-hand 5 and dial, said hour-pinion being arranged to revolve once in twenty-four hours, a minute-hand driven by the central pinion from the main drive-wheel, and the second-hand pinion driven from the central gear, W, through intermediate lantern-wheel and pinion, the 10

pivots of said hands being all in line, all substantially as described.

In testimony whereof I have signed my name to this specification in the presence of two subscribing witnesses.

HIRAM B. MEARS.
